UNITED STATES PATENT OFFICE.

HIRAM Q. HOOD, OF WELLINGTON, KANSAS.

WIND-WHEEL.

SPECIFICATION forming part of Letters Patent No. 361,875, dated April 26, 1887.

Application filed January 21, 1887. Serial No. 225,013. (No model.)

To all whom it may concern:

Be it known that I, HIRAM Q. HOOD, a citizen of the United States, residing at Wellington, in the county of Sumner and State of Kansas, have invented certain new and useful Improvements in Wind-Wheels; and I do hereby declare the following to be a full, clear, and exact description of the invention, such as will enable others skilled in the art to which it appertains to make and use the same.

My invention relates to an improvement in wind-wheels; and it consists in the construction and arrangement of the parts thereof, which will be more fully hereinafter described, and definitely pointed out in the claims.

The object of my invention is to provide a wind-wheel which will be automatic in its working, and at the same time to so construct the several parts as to form a simple, efficient, and powerful wheel with comparatively small expense. I obtain this object by the device illustrated in the accompanying drawings, wherein like letters of reference indicate similar parts in the several views, and in which—

Figure 1 is an elevation of the wheel, showing the canopy and front arms in section and one of the vanes in position. Fig. 2 is a top plan view of the same. Fig. 3 is a vertical sectional view of the hollow shaft.

In the drawings, A represents the supporting-frame, made of a greater width at the bottom than at the top, and is capped by a plate, B, which is rigidly secured thereto, it being provided with a circular opening in its central portion, through which a vertical hollow shaft, made of any suitable material, passes. This shaft C is journaled at its lower end in a bearing, c, which is made of conical shape, having an opening extending therethrough of different diameters, the upper being greater than the lower portion, thereby forming a shoulder, as at c', upon which the shaft C rests, which is in turn somewhat reduced in circumference, thereby forming a shoulder, as at c'', which comes in contact with the said shoulder c' on the bearing c.

c' is a ring, of steel or other suitable material, interposed between the shoulders c' and c'' to prevent wear on the said shoulders. The bearing c is placed on and rigidly secured to cross-pieces b b, which rest on and are secured to

braces a a of the supporting-frame A. The hollow shaft C is extended down below the bearing c for some distance.

D indicates a collar surrounding the shaft 55 C a short distance above the bearing c, it being rigidly secured thereto, and is provided with a bevel-gear on its lower portion, which meshes with a gear-wheel situated on the end of a horizontal shaft, d, which is journaled in 60 the brace-pieces a' a' on the frame A. This shaft d has a pulley-wheel on its outer end, over which a suitable belt is placed, which is to be connected to a pump or other devices requiring power to drive or manipulate them. 65

The upper portion of the shaft C is somewhat enlarged, as shown in Fig. 3, and is surrounded by collars E E', which are rigidly secured thereto in any suitable manner. The lower collar, E, is placed in such position on 70 the shaft C that it will at all times come in contact with the plate B on the top of the frame A, thus forming a supplemental bearing and taking a portion of the weight off from the bearing c. This collar E may be placed 75 somewhat above the plate B, if desired, and the whole weight thrown on the bearing c.

Secured to the collars E and E' are a series of radial arms, e and e', having their ends mortised or otherwise secured in said collars. 80 These arms e e' are six in number, but as many may be used as are desired. Braces e'' are placed on the inner ends of the lower arms, e, and extend upward and outward to the ends of the upper series of arms, e', where they are 85 secured, thus forming a secure brace for the said upper arms. This upper series of arms, e', are also braced, and thereby prevented from spreading, by cross-pieces e''.

F represents a series of uprights or supports placed at an incline, and secured on the upper sides of the upper series of arms, e', and the edge of the collar E', and are braced and held in position by a circular top, f, which also forms a top or shield for the central shaft. 95 To these uprights is also attached a canopy, F', which extends out from the top f, and serves as a protector for the mechanism entire of the wheel. This canopy is supported by suitable ribs and braces attached to the said top portion and uprights. 100

Hinged to the sides of the outer ends of the

radial arms $e e'$, and adapted to be swung in or out, are vanes or wings G, (one only being shown in the drawings,) as shown in Figs. 1 and 2. These vanes are to be attached to the arms $e e'$ by suitable hinges, as g , secured to the upper portions of the said vanes and and the upper arm, e' , and to the lower arm, e , and central portions of the vanes, thereby leaving the lower parts of the vanes extending below the arms. These vanes G are constructed of suitable material and made in trough shape, having two outwardly-inclined sides and a bottom or back portion and open front, thus forming a bucket or trough. These vanes are braced or banded and securely held together by metal strips $h h$, attached to the top, bottom, and central portions thereof, and bolted or in any other manner secured thereto. The central strip is extended entirely around the same across the open face of the vane, and the ends are united and carried out somewhat, where a suitable loop, h' , is attached, which aids in securing the ends of said central band together. By this construction it will be seen that it will be impossible in any way to spread the sides of the vanes apart.

Secured to the arms $e e'$, on the sides of the outer ends thereof, and on the opposite side to the one on which the vanes are secured, is a deflector, H, consisting of a strip of wood or other material of angular formation, with one side slightly curved, it being extended out for some distance and adapted to deflect the wind that would be driven through the frame-work of the wheel into the trough-shaped vanes, and also to prevent the wind from going into said vanes when they are drawn in, as shown in dotted lines in Fig. 2.

Running up through the central cylinder or shaft, C, is a series of governor-rods, i , which extend up, and are connected to centrifugal governors I, and all secured to a circular block, i' , at their lower ends. The governors I are constructed of a horizontal rod with a downwardly-extending portion, on which is loosely mounted an iron ball, K. These rods are pivotally secured near their inner ends to the uprights F, and allowed a rocking motion, so that the weighted end may be thrown up or lowered, as may be desired. Attached to the governors I at or about their centers are connecting-rods k , which are extended down and connected to the arms l of cranks L, which cranks are journaled in a suitable box-bearing, l' , on the lower arms, e , and running laterally thereon. This crank L is provided with a series of arms, l and l' , bent at right angles to each other, so that when one of said arms assumes a vertical position the other is at a horizontal. To the lower opposite crank-arm, l' , on the opposite side of the arm e , is secured a connecting rod or link, m , which is extended out and hooked or fastened to the loop h' on the fan or vane H, so that when the weighted end of the governor is thrown up it draws the vane in, or when down throws it out.

In making my vanes or fans in the shape

above described I obtain a much more powerful wheel. As will be readily seen, the wind is thrown into the bucket or trough, and is not allowed to be deflected out therefrom, as is done in other wheels, but its force is all expended on the fan, thereby producing a greater velocity of the wheel. When the fans or vanes are drawn in, the wheel is cut off from the wind, and the arms may be extended so as to make a perfect inclosure of the vanes by having the outer edges of the same come in contact with the deflector, if desired.

It will thus be seen that the normal position of the vanes is as shown when they are thrown out, and if the wheels should be impelled too rapidly the weighted end of the governor will immediately be thrown out and up by centrifugal force, thereby drawing up the arm l of crank L to a vertical position and the arm l' back to a horizontal position, which in turn draws the vane in, as above described.

When it is desired to stop the wheel and prevent it from working, thereby preventing wear, it is only necessary to draw down on the governor-rods $i i'$, and thereby force the weighted end of the governor up and draw in the vanes. This position may be retained by any suitable device secured to the lower ends of the rods $i i'$ and then attached to the frame, or in any other suitable manner.

It is obvious that many minor changes in the construction and arrangement of the parts of my invention could be made and substituted for those shown and described without in the least departing from the nature and principle of my invention.

I am aware that wind-wheels have heretofore been constructed with centrifugal automatic cut-offs, and such construction I do not broadly claim.

Having thus described my invention, what I claim as new, and desire to secure by Letters Patent, is—

1. In a wind-wheel, the combination, with a central hollow shaft provided with suitable bearings and having radial arms extending out therefrom, of a series of trough-shaped vanes hinged to said arms and constructed of two oblique sides extending outward at an angle from a central vertical strip, and means, as described, for re-enforcing the said vanes, as herein specified.

2. In a wind-wheel, the combination, with a hollow shaft having a series of collars thereon, and arms secured to said collars, of a series of trough-shaped vanes secured to the said arms, deflectors secured to said arms adapted to deflect the wind into said vanes, and suitable bearings and supports, substantially as described.

3. In a wind-wheel, the combination, with the supporting-frame, of a hollow vertical shaft mounted therein, a collar connected thereto having a bevel-gear thereon, a horizontal shaft, as d , journaled in the supporting-frame, having a bevel-gear on one end thereof meshing with the gear on the vertical shaft, a

- 5 pulley on the opposite end of the horizontal shaft, a conical bearing, in which the hollow vertical shaft is journaled, mounted on cross-beams in the lower supporting-frame, radial arms secured to and extending out from said shaft, and trough-shaped vanes mounted on one side of said radial arms and deflectors on the other side in proximity to said vanes, substantially as described.
- 10 4. In a wind-wheel, the combination, with the supporting-frame having a hollow shaft mounted therein, of a series of radial arms extending out from and secured to said shaft, hollow or trough-shaped vanes secured to said 15 arms, deflectors secured to the opposite sides of said arms, a governor having a weighted portion adapted to draw in said vanes, and rods extending through said hollow shaft, substantially as described.
- 20 5. In a wind-wheel, the combination, with the supporting-frame, of a hollow vertical shaft mounted therein, a series of collars se-
- cured to said shaft, a series of radial arms secured to said collars, a series of vanes hinged to said arms, a series of uprights mounted on 25 said shaft and arms, centrifugal governors pivoted to said uprights, and a canopy or top mounted thereon and extending over the entire mechanism, substantially as described.
6. In a wind-wheel, the combination, with 30 the frame-work A, of the hollow shaft C, journaled in a bearing, c, arms e e', extending out from and attached to said shaft, trough-shaped vanes G, hinged to said arms, deflectors H, secured to said arms, governors I, and rods i, 35 to control said governors, and the connecting-rods k and m, and crank L, all arranged in the manner specified, substantially as described.

In testimony whereof I affix my signature in presence of two witnesses.
